[57] CLAIM

The ornamental design for a patient monitor, as shown and described.

DESCRIPTION

FIG. 1 is a front perspective view of a patient monitor showing my new design;

FIG. 2 is a left side elevational view thereof;

FIG. 3 is a front elevational view thereof;

FIG. 4 is a rear elevational view thereof;

FIG. 5 is a top plan view thereof; and

FIG. 6 is a bottom plan view thereof.

The broken line showing of the display, controls and connector on the monitor is for illustrative purposes only and forms no part of the claimed design.

*Fig. 1.**Fig. 2.*

*FIG. 3.**FIG. 4.*

fig. 5.

fig. 6.
